GOLF PUTTER

Robert J. Mader, 1218 Arlington,
Torrance, Calif. 90501

Filed May 9, 1968, Ser. No. 11,869

Term of patent 14 years

U.S. Cl. D34—5
Int. Cl. D21—03

FIG. 1 is a perspective view of the putter, showing my new design,

FIG. 2 is a side elevation view of the putter head,

FIG. 3 is a top plan view of the putter head,

FIG. 4 is a side elevation of the putter head from the side opposite to that shown in FIG. 2,

FIG. 5 is a bottom plan view of the putter head,

FIG. 6 is an end elevation view of the putter head, and

FIG. 7 is an end elevation view of the putter head from the end opposite to that shown in FIG. 6.

The shaft has been omitted from FIGS. 2-7 for convenience of illustration.

I claim:

The ornamental design for a golf putter, as shown and described.
